UNITED STATES PATENT OFFICE.

STEPHEN ANDRÉ BRANDON, OF LEIPSIC, GERMANY, ASSIGNOR TO AARON VAIL ROWLEY, OF FRANKFORT-ON-THE-MAIN, GERMANY.

MACHINE FOR DRILLING BUTTONS.

SPECIFICATION forming part of Letters Patent No. 790,554, dated May 23, 1905.

Application filed June 24, 1903. Serial No. 162,879.

To all whom it may concern:

Be it known that I, STEPHEN ANDRÉ BRANDON, a subject of the King of Great Britain, and a resident of Leipsic, in the Kingdom of 5 Saxony and Empire of Germany, have invented certain new and useful Improvements in Machines for Drilling Buttons, of which the following is a specification.

My invention relates to button-drilling machines, and has for its object to provide an improved button-holding chuck for such machines, such chuck being so constructed as to afford an efficient support for the central portion of the button through which the perforations are made.

The invention will be fully described hereinafter and the features of novelty pointed out in the appended claims.

Reference is to be had to the accompanying drawings, in which—

Figure 1 is an elevation, partly in section, of a portion of a chuck embodying my invention. Fig. 2 is an end view thereof. Fig. 3 is a perspective view and a cross-section of 25 the button-supporting plate shown in Figs. 1 and 2. Fig. 4 is a longitudinal section of another form of my invention. Fig. 5 is a corresponding end view. Fig. 6 shows a third form of my invention partly in section, and 30 Fig. 7 is a face view of the structure shown in Fig. 6.

According to the structure shown in Figs. 1, 2, and 3, the chuck comprises a series of elastic arms *a*, which are adapted to be pressed 35 together in any suitable manner, as by means of the usual casing engaging the beveled surfaces *b*. To one of these arms *a* is attached by a screw *d* or otherwise a button-holding plate *c*, extending transversely across, so as to 40 be in position to form a backing for the button. This plate has the required number of perforations and may be dished to suit the form of the button, as shown in Fig. 3. The outer portion of the plate is adapted to rest 45 against a support formed by shoulders on the arms *a*, as shown best in Fig. 1. Thus the button-holding plate is firmly held in position

without, however, interfering with the contracting or expanding movement of the chuck.

As illustrated by Figs. 4 and 5, the supporting-plate *c*, instead of being attached to one of the arms *a*, is carried by an axially-arranged stem *e*, the rear end of which is secured to the body or shank of the chuck. In this construction also the edge of the plate *c* 55 rests against shoulders provided on the arms *a*.

In Figs. 6 and 7 the plate *c* is provided with arms *f*, which extend between the jaws of the chuck-arms *a* and are at their outer ends secured to a stationary support—such as the 60 work-plate *h*, for instance—by means of screws *g*. It will be understood that in this construction the spaces between the arms *a*, or at least their jaw ends, will be wider than in the structures illustrated by Figs. 1 to 5. 65 The work-plate *h*, in conjunction with the arms *f*, forms a support for the edge portion of the plate *c*, so that in each of the three constructions shown the button-holding plate has its edge portion firmly supported. 70

What I claim as new, and desire to secure by Letters Patent, is—

1. In a machine for drilling buttons and the like, a chuck provided with arms extending alongside each other and secured at one end 75 while the other ends of said arms are free, and a button-supporting plate supported at its edge portion and located within said chuck at the free ends of said arms.

2. In a machine for drilling buttons and the like, a chuck provided with arms extending alongside each other and secured at one end, the other ends of the arms being free, and a button-supporting plate located within the 80 chuck and having its edge portion in engagement with the free ends of said arms. 85

3. In a machine for drilling buttons and the like, a chuck provided with arms extending alongside each other and secured at one end, while the other ends are free, said arms having internal shoulders at their free ends, and a button-supporting plate located within the 90 chuck and engaging said shoulders with its edge portion.

4. In a machine for drilling buttons and the like, a chuck provided with movable arms, and a continuous button-supporting plate located centrally of the chuck and secured directly to one of said arms so as to be movable therewith relatively to the other arms.

5 In testimony whereof I have signed my name

to this specification in the presence of two subscribing witnesses.

STEPHEN ANDRÉ BRANDON.
